Primary Examiner—Doris Clark(74) *Attorney, Agent, or Firm*—Price, Heneveld, Cooper, DeWitt & Litton(57) **CLAIM**

I claim the ornamental design for an extrusion for a fence system, as shown and described.

DESCRIPTION

FIG. 1 is a front perspective view of an extrusion for a fence system, showing my new design;
 FIG. 2 is a right side elevation view thereof;
 FIG. 3 is a left side elevation view thereof;
 FIG. 4 is a top plan view thereof;
 FIG. 5 is a bottom plan view thereof;
 FIG. 6 is a front elevational view thereof; and,
 FIG. 7 is a rear elevational view thereof.
 The claimed design has been broken in the center to indicate indeterminate length.
